UNITED STATES PATENT OFFICE

2,058,292

TRI-PLUG

George B. Benander, Yalesville, Conn., assignor
to Monowatt Electric Corporation, Bridgeport,
Conn., a corporation of Connecticut

Application May 2, 1934, Serial No. 723,534

3 Claims. (Cl. 173—334)

My invention relates to a multi-outlet plug or tri-plug. Multi-outlet plugs or tri-plugs are provided to increase the number of outlets from a receptacle. When such a plug is used in a duplex receptacle in which two outlets are provided, it has been found that not all of the outlets provided in the tri-plug could be utilized, the reason being that one of the side outlets of the tri-plug is adjacent to the other outlet of the receptacle. Thus when the other outlet of the receptacle is used, it is impossible to insert an attachment cap in the adjacent side outlet of the plug.

An object of my invention is to provide an improved multi-outlet or tri-plug in which all of the outlets may be utilized in the plug when used in connection with a duplex receptacle. Another object of my invention is to provide a tri-plug of simple construction, easy to assemble and of low cost of manufacture.

What I consider to be novel and my invention will be better understood by reference to the following specification and appended claims when considered in connection with the accompanying drawing in which Fig. 1 is a perspective view of my improved tri-plug located in a duplex receptacle; Fig. 2 is a perspective view of the tri-plug with one part of the body removed; Fig. 3 is an exploded view of the contact members and spacer of the tri-plug, and Fig. 4 is a perspective view of one part of the body with the contacts removed.

Referring to the drawing, Fig. 1 shows a duplex receptacle 10 with two outlets 11 and 12. The usual face plate 13 is provided. My improved tri-plug 14 is inserted in the outlet 11. An attachment cap 15 on the end of cord 16 is connected to one of the side outlets of the tri-plug 14. Attachment cap 17 on the end of cord 18 is connected to the other outlet 12 of receptacle 10. As may be seen in Fig. 1 the other outlets of tri-plug 14 may readily be utilized by connecting attachment caps to each of them. As pointed out above, it has been the usual practice to so form the tri-plug that when it is connected to one of the outlets, as outlet 11, of a duplex receptacle the side outlets are located along the longitudinal axis of the receptacle. When so located, one of the side outlets is adjacent to the other outlet of the duplex receptacle. It is then only possible to use either this side outlet or the other outlet of the duplex receptacle and it is not possible to use both of these outlets. The reason for this has been the fact that the two slots necessary in each of

the outlets of the duplex receptacle extend longitudinally of the receptacle. The prong of the tri-plug and the spring contact blades have formerly been located in a common plane, as it was believed necessary for the securing of the contacts in the body of insulating material, so that when these tri-plugs are inserted in the openings of one of the outlets of the duplex receptacle the side openings are necessarily located in the longitudinal axis of the receptacle. As better indicated in Figs. 2 and 3, tri-plug 14 is provided with contacts 19 and 20 each consisting of a contact prong 21 and 22 respectively and three spring contact blades 23, 24, 25 and 26, 27, 28, respectively, which extend in planes at right angles to the contact prongs. The tri-plug 14 is provided with a body member consisting of two identical halves 29 and 30 of insulating material. The dividing plane of the body member is parallel to the contact prongs 21 and 22 and also perpendicular to the plane of the spring contact blades. Openings are provided in the sides and one end of the tri-plug 14 through which the contact prongs of attachment caps are adapted to pass. The spring contact blades of contact 19 are located in line with one of the openings of each of the outlets of the side and top of tri-plug 14. The spring contact blades of contact 20 are similarly in line with the other openings of each of the outlets. To reinforce the contact prongs of attachment caps inserted in tri-plug 14 and thus maintain contact pressure between the spring contact blades and the prongs, integral projections 31 and 32 are provided extending within two parts or halves 29 and 30 of the body member of tri-plug 14 and forming plane surfaces in line with one side of each of the openings in the tri-plug 14. The prongs of an attachment cap inserted in any one of the openings lie against the plane formed by these projections 31 and 32. To rigidly secure the contacts 19 and 20 in spaced relation and also to insure the proper spacing of the contact prongs 21 and 22 since it is impossible with the contact prongs 21 and 22 extending parallel with the plane of division of the body member to provide slots in the body member in which the prongs may be seated, a plate 33 of insulating material is provided with end recesses 34 and 35 in which the contact prongs 21 and 22 are adapted to rest. Plate 33 is secured in position in the two halves or parts of the body member by means of integral projections 36 and 37. In the assembly of the tri-plug the contacts 19 and 20 are located in one of the halves as "or

example part 29, two of the spring contact blades of each contact being located between the side walls of the part 29 and the central projection 31. The plate 33 is then located in position between the contact prongs 21 and 22 resting between projections 36 and 37. The other part or half 30 is then placed in position and secured by a bolt extending through an opening 38 provided in projection 31.

10 From the foregoing it may be seen that a tri-plug is provided which is of simple construction, easy to assemble and of relatively low cost of manufacture. In addition, the contact blades are provided in a plane at right angles to the plane of the contact prong so that when the tri-plug is used in a duplex receptacle all of the outlets of the tri-plug may be utilized.

What I claim as new and desire to secure by Letters Patent of the United States, is:

20 1. A tri-plug comprising a body member having two identical halves of insulating material, openings in the sides and ends of said halves of insulating material for the passage of contact prongs, two contact members having three spring contact blades each located in line with one of said openings and a contact prong extending in a plane at right angles to the plane of said blades, a plate of insulating material located between and holding said contact members in spaced relation, and integral projections from said body member to hold said plate in a plane at right angles to the planes of said contact prongs.

2. A tri-plug comprising a two-part member of insulating material, openings in the sides and one end of said body member for the passage of prongs of an attachment cap, integral projections within said body member in line with said openings forming a wall which the prongs may engage on entering said openings, spring contact blades in line with said openings, contact prongs connected to said blades and extending parallel to the plane of division of said body member, a plate of insulating material located between and holding said contact prongs in spaced relation, and integral projections from said two-part member to hold said plate in a plane at right angles to the planes of said contact prongs.

3. A tri-plug comprising a body member having two identical halves of insulating material, openings in the sides and ends of said halves of insulating material for the passage of contact prongs, two contact members having three spring contact blades each located in line with one of said openings and a contact prong extending in a plane at right angles to the plane of said blades, and a plate of insulating material located between and holding said contact members in spaced relation, said plate being positioned between integral projections within said body member and extending in a plane at right angles to the planes of said contact prongs.

GEORGE B. BENANDER.
